CHARLES A. BAUMLER, OF BUFFALO, NEW YORK, ASSIGNOR TO THE BUFFALO SLED COMPANY, OF BUFFALO, NEW YORK, A CORPORATION OF NEW YORK.

WHEEL-MOUNTING.

1,401,939.

Specification of Letters Patent. Patented Dec. 27, 1921.

Application filed March 17, 1920. Serial No. 366,661.

To all whom it may concern:

Be it known that I, CHARLES A. BAUMLER, a citizen of the United States, residing in Buffalo, in the county of Erie and State of New York, have invented new and useful Improvements in Wheel-Mountings, of which the following is a specification.

This invention relates to a mounting which is more particularly designed for the 10 wheels of toy wagons although the same may also be used for other purposes.

The objects of this invention are to provide a retainer for the rollers of the bearing which is simple, efficient and inexpensive; 15 also to improve the means for confining the roller in engagement with the bearing surfaces, and also to provide superior means for retaining the cap on the hub of the wheel containing the roller bearing.

20 In the accompanying drawings:

Figure 1 is a fragmentary longitudinal section of a wheel equipped with my improvements. Fig. 2 is a cross section of the same taken on line 2-2, Fig. 1. Figs. 3 and 25 4 are perspective views of two roller sections and their retainers forming part of my invention. Fig. 5 is a plan view showing the form of the blank from which one of the roller retainers is constructed. Fig. 6 is an 30 elevation of one end of the casing of the roller bearing. Fig. 7 is an elevation of the opposite end of the same with some of the fastening lugs bent into place and others in their unbent position. Fig. 8 is a plan view 35 of the front hub section and one form of the cap attached thereto. Fig. 9 is a perspective view of another form of hub cap embodying my invention.

Similar characters of reference refer to 40 like parts throughout the several views.

10 represents the metal axle of a toy wagon or other wheeled vehicle which in this instance is secured to the underside of a wooden bolster 11 by a rivet 12 or otherwise. 45 Upon the end of this axle is journaled a wheel which may be variously constructed but which, as shown in Figs. 1 and 2, preferably comprises a hub having tubular front and rear sections 13 and 14 which are 50 secured by rivets 15 to the opposite sides of spokes 16. Within the sections of this hub is arranged the casing 17 of the roller bearing which is of metal and of tubular form. One end of this casing, for example the rear 55 end thereof, as shown in Figs. 1 and 6, is

provided with a fixed head 18 which has the form of an annular flange projecting inwardly from the body of the casing. The opposite end of the casing is provided with a removable head 19 which is preferably 60 constructed in the form of a ring and which is detachably connected with the casing by means which preferably consists of a plurality of notches 20 formed in the edge of the ring shaped head, and a plurality of lugs 65 21 arranged at the front end of the casing and projecting through the notches of the ring shaped head and bent against the outer side of the same. In Fig. 7 the lower and right hand lugs 21 are thus bent into place 70 while the upper and left hand lugs are still unbent. In order to limit the rearward movement of the casing in the hub the rear section of the latter is provided at its rear end with an inwardly turned bead or shoulder 75 22 which is engaged by the rear end of the casing, as shown in Fig. 1. A washer 23 is preferably interposed between the rear end of the hub and the bolster. The hub is confined on the axle by a cotter pin 24 passing through an opening in the axle in front of the hub, a washer 25 being preferably arranged on the axle between this pin and the front end of the casing.

The front end of the hub, casing and axle 85 are inclosed by a cap 26 which slips over the hub and is detachably connected therewith by one or more locking lugs 27 preferably bent laterally out of the metal of the hub at the front end thereof and each engaging 90 with a bayonet slot in the adjacent part of the circular body of the cap. This slot preferably comprises an inclined rear inlet portion 28 and a reentrant front portion 29 forming a shoulder 30 between the front and 95 rear portions of this way. In Figs. 1 and 8 this bayonet slot extends from the bore to the periphery of the hub cap while in Fig. 9 this slot is closed on its outer side by a cover 31 so that the same only opens toward 100 the inner side of the casing. The rear ends of the slots in the cap are engaged with locking lugs and then the cap is pushed rearwardly whereby a rotary motion is imparted 105 to the hub by the oblique rear parts 28 of the slots. During the last part of this rotary motion of the hub cap the reentrant parts of its slots brings the shoulders 30 thereof into engagement with the locking lugs 27 and thereby holds the cap against 110

accidental displacement. To secure this result the parts are so proportioned that the rear end of the cap bears against the base 32 of the front hub section and necessitates 5 springing the cap slightly in order to engage its shoulder 30 with the lugs 28.

Between the inner side or bore of the bearing casing and the periphery of the axle are 10 a plurality of bearing rollers 33 which are arranged parallel and in an annular row so that the outer sides of the same engage the casing and the inner sides of the same with the axle.

For the purpose of enabling these rollers 15 to be easily inserted into the casing and retained in their proper working position a roller retaining device is provided which in its preferred form is constructed in two sections each of which is adapted to receive 20 one-half of all the rollers, so that the rollers are in effect divided into two semi-circular rows or groups.

In its preferred form each of these roller 25 retainers comprise two longitudinal bars 34 which are arranged lengthwise at opposite sides of the set of rollers and two cross bars 35 which connect the corresponding ends of the longitudinal bars are arranged at opposite ends of the set of rollers. The 30 longitudinal bars are constructed of flat metal and so arranged that the flat sides of the same are parallel with a plane arranged lengthwise and radially relatively to the axis of the bearing, and each of said cross 35 bars is also constructed of flat metal and so arranged that its flat sides are parallel with a plane arranged radially and transversely relatively to the axis of the bearing. Each of the cross bars is curved concentri- 40 cally with the axis of the bearing, or substantially so, and is provided with a row of pivot openings 37 in which are journaled the trunnions or reduced necks 36 on the adjacent ends of the rollers 33, as shown in Figs. 45 1, 3 and 4. Each of these retainers is preferably formed integrally from metal by first stamping a blank of the form shown in Fig. 5, which consists of two longitudinal bars connected at their opposite ends by two curved cross bars, these several bars being 50 all arranged in the same plane, and the

cross bars being provided with the pivot openings. The cross bars are now bent at right angles to the longitudinal bars and during this bending operation the openings 55 of the cross bars may be engaged with the trunnions of the rollers for retaining the latter in parallelism with each other. In the assembled position of the parts the longitudinal bars of one roller retainer engage the longitudinal bars of the other roller retainer so that the two retainers together form practically a continuous annular retainer which completely fills the space between the bearing casing and axle and holds 60 the rollers reliably against displacement. 65

This retainer is therefore not only efficient in operation, but the same is also very strong and durable and on account of its simplicity the cost of producing the same is 70 comparatively low rendering the same particularly suitable for use in toy wagons where an inexpensive retainer is required.

I claim as my invention:

1. A wheel mounting comprising a plurality of rollers arranged parallel and adapted to surround an axle, a cylindrical casing engaging its inner side with the outer side of said rollers and provided at one end 75 with an integral inwardly projecting head having the form of an annular flange, and a removable head detachably connected with the other end of said casing and having the form of a ring.

2. A wheel mounting comprising a plurality of rollers arranged parallel and adapted to surround an axle, a cylindrical casing engaging its inner side with the outer side of said rollers and provided at one end 80 with an integral inwardly projecting head having the form of an annular flange, and a removable head detachably connected with the other end of said casing and having the form of a ring, said ring shaped head and the adjacent end of the casing 85 being connected by providing said ring shaped head in its edge with notches and providing the respective end of said casing with lugs which engage with said notches and are bent inwardly against the front 90 side of said ring shaped head.

CHARLES A. BAUMLER.
